JOHN H. BARR, OF NEW YORK, N. Y., ASSIGNOR TO REMINGTON TYPEWRITER COMPANY, OF ILION, NEW YORK, A CORPORATION OF NEW YORK.

TYPE-WRITING MACHINE.

1,311,675.

Specification of Letters Patent. Patented July 29, 1919.

Application filed March 31, 1917. Serial No. 158,913.

To all whom it may concern:

Be it known that I, JOHN H. BARR, citizen of the United States, and resident of the borough of Manhattan, city of New York, in 5 the county of New York and State of New York, have invented certain new and useful Improvements in Type-Writing Machines, of which the following is a specification.

My present invention relates to printing 10 mechanism for typewriting machines, and its principal object is to provide improved type bar mechanism including devices for operating the type bars to cause them to print and for controlling their position to 15 vary the case or select the types.

To the above and other ends which will hereinafter appear my invention consists in 20 the features of construction, combinations of devices and arrangements of parts herein- 25 after described and particularly pointed out in the claims.

The preferred form of my invention is 30 illustrated in the accompanying drawings wherein—

25 Figure 1 is a front to rear vertical sectional view of a typewriting machine embodying my invention, parts of the machine being omitted.

30 Fig. 2 is a transverse vertical sectional view, taken on planes indicated by the broken dotted line xx in Fig. 1 and looking rearward.

35 Fig. 3 is a view corresponding to Fig. 1 but showing the position of the parts when the type bars are shifted to print in upper case.

Fig. 4 is a perspective view illustrating 40 more especially the mechanism for varying the case position of the type bars.

Fig. 5 is a perspective view on a reduced scale of a support for the key levers and certain other parts.

Fig. 6 is a view of one of the type actions 45 on a reduced scale.

Referring first to Figs. 1 and 2, the main 50 frame of the machine is shown as comprising side plates 1 and a rear plate 2 provided with ears 3, the side plates and rear plate being secured in fixed relation by screws 4.

55 A supplemental U-shaped plate 5 for protecting the keyboard is secured to the side plates 1 by screws 6. The side plates are cut out as indicated at 1^a. The top plates that surmount said side plates are omitted from the drawing. A platen 7, diagram-

matically illustrated, is mounted in a carriage for movement back and forth across the top plate under the control of carriage feeding devices, which are not herein disclosed but may be of any desired construction.

Type bars 8, each provided at the outer end of its shank or body portion with a type block 9 having two types, are disposed in an arc below the platen and are adapted to 60 coöperate with the front face thereof. The type block is slotted to straddle the type bar, the outer end whereof may be curved as indicated along its top edge to promote favorable contact with the type block which 65 is secured in place in any suitable way as by soldering. The type bars are arranged in guide slots, indicated at 10, which guide slots are cut in a vertically disposed type bar support or segment 11 radially of a 70 point z' below the printing point. Except the center type bar or bars, the type bars, as 75 is well understood, are bent just below the type blocks so that the type blocks shall stand vertically when in printing position. 80 The bends center at the point z' . The horizontal line extending forward through the point z' is indicated at z . The type bars 8 are perforated at their inner ends and have a common pivot wire 12 passing through the 85 perforations which wire is suitably secured to the segment 11. The type bars are horizontally disposed and near their printing ends are normally supported on a rest or pad 13 secured in a groove formed in a segmental member 14 which is arranged vertically and forward of the type bar segment, and is suitably secured thereto and supported thereby as by rods or bars 15 extending 90 forward from the segment near its ends, 95 and to which the end portions of the segmental member are fixed.

The type bar support or element comprising the segment proper 11 and the supplemental segment or member 14 is mounted 100 for vertical shifting movements, and for this purpose lateral arms or brackets 16 are secured to the segment 11 in any suitable manner, as by screws 17 and dowels 18. The supporting and guiding means for the 105 segment comprise two pairs of parallel bars or arms 19 and 20, both pairs substantially horizontally disposed, the pair 19 being arranged above the pair 20. The arms 19 are spaced apart at each side of the machine 110

and their forward end portions are pivotally connected with the segment extensions 16. The extensions 16 terminate in rearwardly extending parallel ears 16^a which receive shoulder screws 21 that pass loosely through the arms 19. Each shoulder screw has a hexagonal head terminating in a rounded top 21^a. The tops 21^a coöperate with the heads of screws 22 that are threaded into the side plates 1 and project inward therefrom, said screws being held in adjusted positions by means of jamming nuts 22^a. The heads of the screws 22 have no nicks, the nicks being preferably in the ends of the shanks. The screws 21 and 22 coöperate to prevent lateral vibration or displacement of the segment. The rear ends of the arms 19 have fixed pivots 23 projecting inward from the sides of the plates 1.

20 The lower pair of arms 20 are arranged within the base near the sides thereof, their rear end portions being provided with hubs 24 (Fig. 4), which are secured by pins or set screws 25 to a rock shaft 26 which has bearings fixed on the plates 1. The forward ends of the arms 20 are pivotally connected to a frame or supplemental portion of the segment 11, which frame is adjustably connected to said segment and carries stops for limiting the up and down movements thereof. Said frame comprises two vertical rods or bars 27 and a connecting cross bar 28 (Figs. 1, 3 and 4). The rods 27 are arranged at the sides of the segment 11. The upper end portion of each rod is reduced and screw threaded as indicated at 27^a. The threaded portions engage in threaded openings in the extensions 16 and below such extensions carry locking nuts 29. The lower ends of the rods 27 are formed with hexagonal heads 30 and below these heads terminate in reduced threaded portions 31 on which are nuts 32. The cross bar 28 is confined between the hexagonal heads 30 and the nuts 32 which serve as clamps to make the frame comprising the rods 27 and the cross bar 28 rigid. By loosening the nuts 32 the rods 27 may be rotated on their axes by a spanner or other tool applied to the hexagonal heads 30, the nuts 29 of course being also loosened to permit of such rotation. As a result of such rotation the frame 27, 28 and the segment 11 may be relatively adjusted, and after such adjustment may be rigidly held or set in fixed relationship by tightening or jamming the nuts 29. After thus adjusting or re-adjusting the frame and segment, the nuts 32 of course should be tightened. Brackets 33 are secured to the under face of the cross bar 28 in any suitable way, as by spot-welding, each bracket comprising a pair of downwardly extending ears 34 between which is loosely arranged the forward end of one of the arms 20.

65 Cross pins 35 secured in the ears 34 pivotally connect the arms 20 with the cross bar 28 and consequently with the type bar segment. The end portions of the cross bar 28 project outward beyond the rods 27 and are provided with pads 36 of fiber or the like at their top and bottom faces. These pads constitute stop devices, each pad co-operating with a stationary stop device. The stationary stop devices are constituted by brackets 37 cast as a part of or otherwise suitably secured to the side plates 1, and each bracket, as best shown in Fig. 4, comprises an inwardly extending lug or stop proper 38 and a lower inwardly extending lug 39. The lug 39 is broader than the lug 38 and provides a support for an adjustable stop plate proper 40 which is connected to its support 39 by three screws, the two outer screws 41 being headed and passing upward loosely through the support 39, screwing into threaded openings in the stop plate 40. The middle screw 42 is threaded through the support 39 and abuts against the lower face of the stop plate 40, holding it in its uppermost position as determined by adjustments of the side screws 41. The upper pad 36 on each side of the stop bar co-operates with a lug 38 to limit upward movement of the frame 27—28 and segment 11 while the under pads 36 coöperate with the stop plate 40 to limit downward movements of said parts. Normally the segment is maintained in its upper position, as shown in Figs. 1, 2 and 4, by spring devices, said spring devices comprising a wire spring 43 coiled around the rock shaft 26 at its left-hand side. The inner end of said spring is hooked into an angular bracket 44 screwed to the rear of the frame plate 2, thus providing a stationary anchorage for the spring. The left-hand end portion of the spring is secured in a collar 45 loosely mounted on the shaft 26. The outer end portion of said collar is provided with ratchet teeth which engage with corresponding ratchet teeth formed on the inner face of the left-hand hub 24. The collar is provided with holes to receive a tool by which it may be rotated to provide for varying the tension of the spring 43. After adjustment the spring serves to maintain the collar set by engagement of the two sets of ratchet teeth. The spring 43, acting through the arms 20, normally overcomes the force of gravity and maintains the type bar segment 120 and the frame depending therefrom in upper position with the top stop pads 36 engaged with the lugs 38. In this position the inner or lower case types on the type blocks 9 are adapted for printing.

In order to shift or depress the segment for printing with the outer or upper case types, key operated devices are provided, said devices operating on the shaft 26 to rock it and swing or move the arms 20 and con-

ected parts downward. The key operated devices comprise a bail or member 46 having a body or cross portion 47 and two downwardly bent parallel arms 48 provided with hubs 49 which bear loosely on the rock shaft 26 outside the crank arms 20. A central upstanding rod or arm 50, fixed to the rock shaft 26, is provided with a T-head 51 to which the bail 46 is secured by screws 52 passing downward through the cross portion 47. The construction is such that the central portion of the bail is fixed to the central portion of the rock shaft, the end portions or arms 48 of the bail bearing loosely on the rock shaft. Lateral pins 53 extending outward from the upper end portions of said arms are engaged loosely by the rear ends of horizontally disposed links 54, said links being provided with slots indicated at 55 which receive the pins 53. The forward ends of said links are pivotally connected at 56 with the upwardly extending arms 57 of shift key levers, which further comprise forwardly extending arms 58 and hub portions 59, said arms 58 terminating in shift keys 60. The hub portions 59 bear rotatably on a transverse pivot rod 61 secured at its ends in the side plates 1. Draw springs 62, anchored at their rear ends to stationary pins 63 and at their forward ends hooked into the arms 57, restore the trains of key operated devices comprising the parts 54, 57 and 58 to normal or lower case position after a downward shifting operation and tend to maintain the lever arms 57 engaged with stop pins 64 that project laterally inward from the side plates 1. The construction is such that the keys 60 are independent of each other, the loose or lost motion connection 53, 55 permitting the bail 46 and rock shaft 26 to be rocked by depressing one of the keys 60 without affecting the other key and the parts controlled thereby. The keys 60 are spaced apart, being arranged at opposite sides of the printing keyboard and the angular levers 57, 58 may be kept in proper position on the pivot rod 61 by means of fixed collars 65 which loosely confine the hubs 59 between said collars and the adjacent side plates 1. It will be observed that as a result of the described construction the pull, transmitted to either link 54 actuated by the associate shift key 60, is further transmitted through the pin 53, bail 46 and arm 50 to the middle portion of the rock shaft 26, so that the torsion to which such rock shaft is subjected does not produce unequal motion of the two links or arms 20. Also it will be observed that the shift frame is provided with stop devices comprising the parts 36 and 37 which are independent of the stop devices 64 of the actuating mechanism controlled by the keys 60; also that after the extent of shifting movement of the segment 11 and its depending frame 27, 28 has been determined by the relative adjustment of the stops 38 and 40, the position or location of the segment 11 may be independently varied or set through adjusting the relationship between said segment and its frame 27, 28, as has been described. During the up and down shifting movements of the segment the rounded tops 21^a of the heads of the screws 21 coöperate with the heads of the adjustable screws 22 to assist in guiding the segment, preventing undue sidewise movement or vibration. The screws 22 are so adjusted in respect to the screws 21 that the free up and down shift of the segment is not impeded but any undue side movement is prevented. The heads of the screws 22 are of such diameter that in both lower and upper case positions the rounded tops 21^a are contiguous to said heads so that at all times the segment is guided and controlled in respect to lateral vibration. It will be further understood that a lack of any suitable description may as usual be provided in connection with one of the shift key levers to hold the segment depressed in upper case position. The case shifting mechanism *per se* is not claimed herein but has been made the subject-matter of a divisional application Sr. No. 190,696 filed September 11, 1917.

The actuating mechanism of the type bars will next be described. Each type bar 8 has a heel or pivot portion which is substantially at right angles to the body or shank and is somewhat wider than the body of the bar and this heel portion is formed longitudinally with a slot, indicated at 66. Said slot lies wholly forward of the pivot 12 and approximately at right angles to the body or shank inclining forward and downward, and terminating at its lower end portion in an enlargement 67. This slot operates as a cam slot and through it its type bar is directly connected to a lever or driver which is preferably in the form of a bell crank having a long arm 68 and a short arm 69. The bell cranks or drivers are mounted in slots indicated at 70, said slots being formed or cut radially in the member 14 at its rear side, the pivots 70 of the drivers being supported on said member 14. Each bell crank is substantially in the radial plane of its type bar, the long arm 68 extending under and substantially parallel with the body of the bar, said arm at its rear end being provided with an actuating device or headed pin 71 which engages in the slot 66 and operates the type bar. The head of the pin prevents accidental detachment from the slot but the parts may be readily separated by bringing said head into register with the enlargement 67 which is slightly larger than the head. The shorter arms of the bell cranks extend radially downward and outward and are connected by horizontally disposed or fore-and-aft links 72 with the upstanding arms 73 of another set of

bell cranks which further comprise horizontally disposed arms 74, said bell cranks 73, 74 being arranged in parallel vertical planes and pivoted on a common pivot wire 75, 5 which is supported on a frame that is detachably mounted in the base of the machine, being best illustrated in Fig. 5. Said frame provides supports not only for the bell cranks or levers 73, 74 but also for the 10 key levers hereinafter described. The frame is generally rectangular, comprising a rear bar 76, a parallel front bar 77, connecting end bars 78, and laterally extending lugs 79 and 80. These lugs receive headed screws 81 and 82 which are screwed upward from the under side into threaded thickened portions of the side plates 1, thus detachably securing the frame and the parts mounted thereon to the main frame of the machine. 15 The bar 76 is provided with a series of parallel guide slots 83 at its forward side for the reception of the rear end portions of the bell cranks 73, 74. The vertical arms of these bell cranks, instead of rising directly 20 upward from the pivots 75, are preferably disposed some distance forward of the pivots along the arm 74 so as effectively to clear the cross bar 76, but it will be apparent that these levers 73, 74 are essentially bell cranks. 25 The upstanding lever arms 73 vary in length, increasing progressively from the middle or center to the sides of the system, as will be understood from a consideration of Figs. 1 and 2. The lever arms 69 are all of the same 30 length but since their pivots are at different heights, increasing progressively from the middle to the sides of the system, the arrangement provides for the links 72 which connect the arms 69 with the arms 73, being 35 all parallel with each other and substantially horizontally disposed to give a straight fore and aft pull, these links conforming to the lines in which the planes that contain the lever arms 69 intersect the planes of the 40 lever arms 73. In order to compensate for the variations in the lengths of the arms 73, that is, in order that the upper ends of these 45 varying arms shall all move to the same extent so as to communicate the same extent of movement to their respective type bars, the arms 74 are correspondingly varied, this 50 being preferably effected by variably locating, in respect to the pivot 75, the devices which receive actuation from the key levers. Said devices in the present instance are in 55 the form of headed pins 84. These headed pins engage in longitudinal cam slots indicated at 85 formed in the rear end portions of key levers 86 and 87 which are of the first 60 order. There are two kinds of key levers, differing somewhat in shape, the key levers 86, which are provided with printing keys 88, constituting the two upper rows. The 65 key levers 86 are pivoted on a fulcrum wire 89 which is supported on and extends length- wise of the bar 77, said key levers being guided in parallel slots, indicated at 90, formed transversely of said bar at its rear and under sides. The other key levers 87, 70 whose keys 88' constitute the lower two rows, are pivoted on a common pivot wire 91 forward of and somewhat below the pivot wire 89 and also supported on the bar 77. The key levers 86 curve downward, forward of 75 their pivots, so as to clear the pivot wire 91 which they pass under. It will be understood that by varying the points of connection by changing the positions of the pins 84 the amount of motion communicated to the levers 73, 74, from their connected key 80 levers, may readily be varied. The construction is such that by setting the pin farther from the fulcrum 75, it is brought correspondingly nearer to the fulcrums 89 and 91 so that not only is the motion it receives 85 from the key lever reduced but the amount of motion it communicates to the lever arm 74 is correspondingly reduced. In other words, the motion imparted to the pin 84 is thus reduced and the pin being farther 90 from its own fulcrum 75 further reduces the motion communicated to the lever 73, 74. It is apparent that the longer the lever arm 73 the farther from the fulcrum 75 along the arm 74 is the pin 84 fixed or set. Near their 95 forward ends the key levers coöperate with a stationary slotted guide or comb plate 52. Spring devices for restoring the type bars to normal position after actuation are provided, comprising draw springs 92 which are 100 connected to the lever arms 69 and extend horizontally forward, the forward ends of said springs being hooked over radial hook portions 93 formed along the lower edges of plates 94 that are secured to a segmental 105 angle-plate 95. Threaded through the plates 94 and 95 are supporting screws 96 which are provided with reduced inner ends 97 that form shoulders with the bodies of the screws and fit loosely in holes in the front 110 flange of the segmental member 14. There are three of these screws 96, one at the middle and the other two near the opposite ends of the segmental plate 95, and the construction is such they hold the plate 95 suitably spaced away from and forward of the supporting member 14, the springs 92 holding the plate in a position determined by 115 contact of the shoulders on the screws 96 with the front face of the member 14. By 120 screwing in or out on these screws the plate may be moved backward or forward and the tension of the springs 92 correspondingly varied. It will be understood that when one of the key levers is depressed the bell 125 crank 73, 74 that is directly connected to it is rocked, this motion being transmitted through the pull link 72 to the connected bell crank 68, 69, said bell crank operating through its pin 71 on its cam slot 66 to 130

swing the connected type bar upward and rearward to print against the platen 7. Preferably the type bars are provided with shoulders 98 that, toward the latter part of 5 the type bar movement, coöperate with a universal bar 99 that is comprised in the carriage feeding mechanism, the universal bar being mounted to shift with the segment 11. When said segment is in the topmost or 10 lower case position, the inner type will print as has been stated. When, however, one of the shift keys 60 has been depressed from the full line position shown in Fig. 1 to the full line position shown in Fig. 3, the type 15 bar segment will be lowered or depressed, as has been explained, so that if then one of the printing keys be actuated the outer type on the connected type bar will be caused to print, as will be apparent from 20 the dotted line positions of the parts illustrated in Fig. 3. This figure illustrates the left-hand shift key as depressed. The right-hand shift key not illustrated in said figure will remain in its normal position, since the 25 slot 55 in the associate link will permit the right-hand pin 53 that engages it to move idly forward.

My present invention provides for an effective type action and one which is especially adapted for use in a machine in which the type bars are shiftable to change case.

It will be observed that by my present invention there is provided a type bar comprising a shank or body portion and a heel 35 portion substantially at right angles to the shank portion, said heel portion being adapted for pivotal mounting at its upper end and being also provided with a longitudinally arranged slot; that said slot is likewise substantially at right angles to said shank; that said heel portion is perforated at its end and is provided with an angularly arranged slot between said perforation and the shank or body of the bar; that combined with a platen there is a set, series or 40 system of type bars; that the set of type bars is arranged in an arc of a circle below the platen, said type bars being guided as by radial or converging slots in a support or 45 segment and normally extending forward in a horizontal direction from their pivots and being provided or formed with slots forward of their pivots, said slots being diagonal or inclined forward and downward; 50 that a set of levers are directly connected to the type bars at one side of the pivots or fulcrums of said levers; that said fulcrums are arranged at different elevations, being in a curve or arc of a circle, the center whereof 55 is in the horizontally disposed straight line, z (Fig. 1) below the printing point p , which line contains also the center of the arc containing the type bar pivots; that said levers 60 in the present instance have actuating devices or pins which engage in the slots in the 65 type bars; that the type bars are operated by a set of keys which are connected by trains of devices with the levers aforesaid, the connections of said trains of devices with the levers being at different sides of the fulcrums 70 of said levers from the pin and slot connections of said levers with the type bars; that the points of connections between the trains of devices and said levers are in an arc of a circle, the center whereof is in the horizontal 75 straight line z aforesaid; that said levers in the present instance are bell cranks having their longer arms extending normally substantially parallel with the type bars and their shorter arms lying in radial planes, 80 said shorter arms extending downward and outward, and all being equal in length; that the connections between the printing keys and the bell cranks or levers comprise links which extend under said longer arms substantially parallel therewith, said links being connected to said shorter arms; that the trains of connecting devices or the connections between the keys and the bell cranks aforesaid comprise further a second set of 85 bell cranks; that said second set of bell cranks in the present instance are directly connected with the key levers on which said keys are mounted, such connection being by means of pins and slots, the key levers being 90 provided with cam slots and the second set of bell cranks with engaging pins on their horizontally disposed arms; that the other or upstanding arms of said second set vary in length increasing progressively from the 95 middle to the sides of the system; that said links communicate fore and aft pulls from one set of bell cranks or connecting levers to the other set of bell cranks or connecting levers; that the points of connection of the 100 links with the forward bell cranks are in a common transverse plane forward of another transverse plane containing the points of connection between said links and the rear bell cranks or those connected to the key 105 levers; that said links lie substantially both in the vertical parallel fore and aft planes containing the key levers and their connected bell cranks, and also in the radial or converging planes containing the type bars 110 and the bell cranks connected directly to said type bars; that the links aforesaid while horizontally disposed, generally speaking, are normally inclined at a slight angle to the horizontal and above it but are shiftable 115 downward to a corresponding angle below the horizontal when the case shifting operation occurs; that such case shifting is effected by shifting the slotted support or segment on which the type bars are 120 mounted; that the shiftable element comprises the type bar segment or support proper and the supplemental curved member which is fixed to and carried by said segment and provides a support for the type 125 130

rest as well as being slotted to form bearings for the bell cranks that operate directly on the type bars; that the key levers are mounted in a stationary or non-shifted element which is slotted to provide guide slots for the key levers and has also other slots for the sub-levers or bell cranks which are directly connected to said key levers, this stationary element being readily detached from 10 and replaced in its position in the base of the machine; and that when the type bar segment is shifted the bell crank levers 68—69 shift therewith, and that at this time the links 72 swing about their rear pivotal connections with the stationary bell cranks 73—74, which together with the key levers remain motionless during the shifting operations.

Various changes may be made without departing from my invention.

What I claim as new and desire to secure by Letters Patent, is:—

1. In a front strike typewriting machine, the combination of a set of type bars rotatable about fixed centers, a set of bell cranks directly connected to said type bars and having their longer arms extending normally substantially parallel with said type bars and their shorter arms in radial planes, keys, 25 and connections between said keys and said bell cranks, said connections comprising links extending under said longer arms substantially parallel therewith and connected to said shorter arms.

2. In a front strike typewriting machine, the combination of a set of type bars, a set of bell cranks directly connected to said type bars and having their longer arms extending normally substantially parallel with 30 said type bars and their shorter arms arranged in radial planes, said shorter arms being substantially equal in length, key levers, another set of bell cranks operated directly by said key levers and having upstanding arms which vary progressively in length from the middle to the sides of the system, and fore and aft links connecting said upstanding arms with said radially extending arms.

3. In a front strike typewriting machine, the combination of a set of type bars arranged in an arc of a circle and extending forward from their pivots when in normal position, said type bars being rotatable 55 around fixed centers, a set of bell cranks directly connected to said type bars and having their longer arms extending normally substantially parallel with said type bars, the fulcrums of said bell cranks being in an arc of a circle of substantially larger diameter than the diameter of the circle in an arc of which the pivots of the type bars are contained, keys, and connections between said keys and the shorter arms of said bell cranks,

said connections comprising a second set of 65 bell cranks.

4. In a front strike typewriting machine, the combination of a set of type bars arranged in an arc of a circle and extending forward from their pivots when in normal 70 position, said type bars being rotatable around fixed centers; a set of bell cranks directly connected to said type bars and having their longer arms extending normally substantially parallel with said type bars, 75 the arc of the circle containing the pivots of said bell cranks being substantially larger in diameter than the circle of the arc containing the pivots of said type bars; keys; and connections between said keys and the shorter arms of said bell cranks, said connections comprising a second set of bell cranks and links connecting said second set of bell cranks with the shorter arms of said first recited bell cranks.

5. In a front strike typewriting machine, the combination of a set of type bars arranged in an arc of a circle and extending forward from their pivots when in normal 90 position; a set of bell cranks directly connected to said type bars and having their longer arms extending normally substantially parallel with said type bars; key levers; and connections between said key levers and the shorter arms of said bell 95 cranks, said shorter arms being in radial planes, said connections comprising a second set of bell cranks directly connected to said key levers by pin and slot connections, and links connecting said second set of bell 100 cranks with the first recited bell cranks.

6. In a front strike typewriting machine, the combination of a set of type bars; a set of key levers; and connections between said type bars and said key levers comprising a 105 set of bell cranks having cam connections directly with said type bars, the pivots of said bell cranks being contained in an arc of a circle of substantially greater diameter than is the diameter of the circle in an arc 110 of which the pivots of the type bars are contained, a second set of bell cranks having cam connections directly with said key levers, and a set of links connecting said sets of bell cranks.

7. In a front strike typewriting machine, the combination of a set of type bars arranged in the arc of a circle, keys, and connections between said keys and said type bars, said connections comprising two sets of 120 bell cranks and substantially horizontally disposed links, one set of bell cranks comprising downwardly and outwardly extending arms substantially equal in length and the other set comprising upwardly extending 125 arms which vary progressively in length from the middle to the sides of the system, said links connecting said downwardly ex-

tending arms with said upwardly extending arms and being substantially parallel with each other, the pivots of said first specified set of bell cranks being contained in an arc 5 of a circle of greater diameter than is the diameter of the circle in an arc of which the pivots of the type bars are contained.

8. In a front strike typewriting machine, the combination of a set of type bars arranged in converging planes, a set of levers having pin and slot connections with said type bars and also arranged in converging planes, the pivots of said set of levers being contained in an arc of a circle of substantially 15 greater diameter than is the diameter of the circle in an arc of which the pivots of the type bars are contained, key levers arranged in parallel planes, another set of levers having pin and slot connections with 20 said key levers and arranged in parallel planes, and fore and aft links connecting said sets of levers and lying in the planes of both of said sets of levers.

9. In a front strike typewriting machine, the combination of a set of type bars arranged in converging planes, bell cranks having pin and slot connections with said type bars and also arranged in converging planes, the longer arms of said bell cranks 25 being arranged under and parallel with their associate type bars, key levers, and connections between said key levers and the shorter arms of said bell cranks, said connections comprising a set of levers and a set of links, 30 the pivots of said set of bell cranks being contained in an arc of a circle of greater diameter than is the diameter of the circle in an arc of which the pivots of the type bars are contained.

40 10. In a front strike typewriting machine, the combination of a set of type bars arranged in converging planes, bell cranks having pin and slot connections with said type bars and also arranged in converging planes, the longer arms of said bell cranks being 45 arranged under and parallel with their associate type bars, the pivots of said first specified set of bell cranks being contained in an arc of a circle of greater diameter than 50 is the diameter of the circle in an arc of which the pivots of the type bars are contained, key levers, a second set of bell cranks having pin and slot connections with said key levers and also comprising upwardly 55 extending arms, and means connecting the two sets of bell cranks.

11. In a front-strike typewriting machine, the combination of a set of type bars arranged in converging planes, bell cranks having pin and slot connections with said type bars and also arranged in converging planes, the longer arms of said bell cranks being arranged under and parallel with 60 their associate type bars, the pivots of said

first specified set of bell cranks being contained in an arc of a circle of greater diameter than is the diameter of the circle in an arc of which the pivots of the type bars are contained, key levers, a second set of bell cranks having direct connections with said 65 key levers, and fore and aft links directly connecting said sets of bell cranks.

12. In a front strike typewriting machine, the combination of a set of type bars arranged in an arc of a circle and extending 70 forward from their pivots when in normal position, said type bars having slotted portions forward of their pivots, the slots extending diagonally forward, levers having actuating devices engaging with said slots, 75 said levers being arranged in radial planes corresponding with the planes of the type bars, a set of key levers arranged in parallel vertical planes, and connections between said key levers and said first recited levers. 80

13. In a type bar action, the combination of a series of key levers of the first order having elongated slots in their rear arms, and a series of bell cranks having pins at different distances from the fulcrums of said 90 bell cranks and engaging said slots at different points in their lengths.

14. In a front strike typewriting machine, the combination of a set of type bars, a set 95 of bell cranks directly connected to said type bars and having their longer arms extending normally substantially parallel with said type bars and their shorter arms in radial planes, keys, connections between said keys and said bell cranks, said connections comprising links extending under said longer arms substantially parallel therewith and connected to said shorter arms, and means for shifting said type bars and said bell cranks, the end portions of said links that 100 are connected to said bell cranks participating in the shifting movement.

15. In a front strike typewriting machine, the combination of a set of type bars, a set 110 of bell cranks directly connected to said type bars and having their longer arms extending normally substantially parallel with said type bars and their shorter arms in radial planes, keys, connections between said keys and said bell cranks comprising fore 115 and aft links extending under the longer bell crank arms and at their forward ends connected to the shorter radial arms of said bell cranks, and means for shifting said type bars and said bell cranks, said links 12 shifting at the same time about their rear ends as centers.

16. In a front strike typewriting machine, the combination of a set of type bars arranged in an arc of a circle and extending 125 forward from their pivots when in normal position; a set of bell cranks directly connected to said type bars and having their

longer arms extending normally substantially parallel with said type bars; keys; connections between said keys and the shorter arms of said bell cranks, said connections comprising a second set of bell cranks and links connecting said second set of bell cranks with the shorter arms of said first recited bell cranks; and means for shifting said type bars and said first recited set of bell cranks, said links shifting at the same time about their points of connection with said second set of bell cranks.

17. In a front strike typewriting machine, the combination of a set of type bars; a set of key levers; connections between said type bars and said key levers comprising a set of bell cranks having cam connections directly with said type bars, a second set of bell cranks having cam connections directly with said key levers, and a set of links connecting said sets of bell cranks; and means for shifting said type bars to change case, said first recited bell cranks shifting with said type bars and said links also shifting about their points of connection with said second set of bell cranks.

18. In a front strike typewriting machine the combination of a set of radially arranged type bars, a set of levers directly connected to said type bars and arranged in radial planes corresponding with the planes of the type bars, a set of key levers, another or second set of levers having direct connections with said key levers and arranged in vertical planes corresponding with the planes of said levers, links for communicating direct fore and aft pulls from the members of one of said sets of levers to the members of the other of said sets of levers, and means for shifting said type bars to change case, the first recited set of levers shifting with said type bars and said links also shifting about their points of connection with said second set of levers as centers, said links in one case position making an angle with the horizontal at one side thereof and in the other case position making a corresponding angle at the opposite side of the horizontal.

19. In a front strike typewriting machine, the combination of a platen, a type bar support, means for shifting said type bar support, a set of type bars arranged in radial slots in said support, bell cranks also arranged in radial slots in said supports and having pin and slot connections with said type bars, the pivots of said bell cranks being in a plane forward of the plane of the type bar pivots, key levers, and connections

from said bell cranks to said key levers, said connections comprising horizontally disposed links extending rearward from their connections with the bell cranks, said links turning about their rearward points of connections as centers during the case shifting operations.

20. In a front strike typewriting machine, the combination of a platen, a type bar support, means for shifting said type bar support, a set of type bars arranged in radial slots in said support, bell cranks also arranged in radial slots in said supports and having pin and slot connections with said type bars, the pivots of said bell cranks being in a plane forward of the plane of the type bar pivots, key levers, and connections from said bell cranks to said key levers, said connections comprising horizontally disposed links extending rearward from their connections with the bell cranks, said links turning about their rearward points of connections as centers during the case shifting operations, said connections comprising links which in one case position occupy an angle with the horizontal and in the other case position are shifted to a corresponding angle at the opposite side of the horizontal.

21. In a front strike typewriting machine, the combination of a set of type bars, a set of bell cranks directly connected to said type bars and having their longer arms extending normally substantially parallel with said type bars and their shorter arms arranged in radial planes, said shorter arms being substantially equal in length, key levers, another set of bell cranks operated by said key levers and having upstanding arms which vary progressively in length from the middle to the sides of the system, fore and aft links connecting said upstanding arms with said radially extending arms, said links each normally standing at an inclination to and above a horizontal line, and means for shifting said type bars and said first recited bell cranks, said links as a result of said shifting movement being swung to an angle below the horizontal corresponding to the former angle above the horizontal.

Signed at the borough of Manhattan, city of New York, in the county of New York, and State of New York, this 30th day of March, A. D. 1917.

JOHN H. BARR.
